CLAIM

The ornamental design for a pair of shareable earbuds, as shown and described.

DESCRIPTION

FIG. 1 is a disassembled top perspective view of a pair of shareable earbuds showing my new design;

FIG. 2 is a disassembled bottom perspective view thereof; FIG. 3 is a disassembled front elevational view thereof; and, FIG. 4 is a disassembled cross sectional view, taken along line 4-4 of FIG. 3 thereof.

The broken line showing of the accessory attachment and magnetic ring shown in FIGS. 1-4 is included for the purpose of showing environmental structure and form no part of the claimed design.
